A read only memory on a semiconductor substrate having metal word lines and diffused bit lines with opti-

mized dimensions for a selected performance and storage capacity with the metal lines being along an X dimension and the diffused lines being orthogonally related to the metal lines along a Y dimension. The X dimension for the substrate is given by the relation $X = 2^N \cdot WL \cdot K1$ where 2^N is an integer definitive of the number of words on a metal line where N is any integer power greater than zero; WL is word length which equals the number of storage devices per word selected for a word and K1 is a constant definitive of the average spacing in mils between the storage devices along the first length, and the Y dimension being given by a second relation $Y = K2 \cdot Q/2^N$ where K2 is a constant definitive of the spacing in mils between the adjacent rows of storage devices along the second length and Q is the number of said words. Changing the aspect ratio for an array permits the performance of a read only memory to be changed to a different set of X and Y dimensions.
